Richmond, Va., as trustees

Application February 14, 1942, Serial No. 430,957

20 Claims. (Cl. 258—1.6)

This invention relates to airplane pick-up mechanisms.

A number of devices have been developed for the purpose of permitting airplanes to pick up articles or packages without the necessity for landing, the airplane being provided with a hook adapted to engage a loop in a flexible element connected to the article to be picked up and having a portion suspended between supporting masts for engagement by the airplane-carried hook. The most practicable mechanisms of this character employ a catapult automatically releasable by the pulling of the suspended loop by the airplane-carried hook, to project the article in the direction and preferably at the speed of flight of the airplane, the catapult overcoming the inertia of the load and thus preventing the airplane from having to pick up a dead weight load.

Certain prior types of mechanisms of this character depend upon the actual pull of the hook against the loop to directly mechanically release the catapult, and these types are not particularly advantageous in use because of the substantial pull necessary to release the catapult. Other types of devices provide for the releasing of the catapult upon the transmission of a relatively light pulling force against the loop, easily operated electric switches being provided which are operable upon the picking up of the loop by the hook to energize a solenoid to release a catapult latch. Devices of this character are highly advantageous, but they require either the running of long electric lines for supplying the current for the circuit or the use of storage batteries for this purpose mounted in the catapult.

An important object of the present invention is to provide a novel catapult mechanism for use in conjunction with an airplane-carried pick-up hook wherein the releasing of the catapult is effected very easily upon the picking up of the loop by using a simple fluid pressure operated motor for releasing the catapult latch.

A further object is to provide a novel apparatus of this character wherein a simple valve device is operable upon the picking up of the loop for releasing fluid pressure from one end of the motor whereby fluid pressure in the other end of the motor will become effective for releasing the catapult latch.

A further object is to provide a novel motor in a mechanism of this type wherein any minor leaks which occur through the valve mechanism will have no effect on the operation of the motor, pressures in opposite ends of the motor remaining automatically balanced so that the releasing of air from one end of the motor upon the picking up of the loop will render the motor instantaneously effective for releasing the catapult latch.

A further object is to provide a novel form of an apparatus of this character wherein a single pressure line supplies pressure to one end of the motor and wherein a leakage port through the pressure responsive element of the motor serves to admit air into the other end of the motor to balance pressures therein, the leakage port serving to maintain balanced pressures even if leakage occurs through the valve device.

10 Other objects and advantages of the invention will become apparent during the course of the following description.

In the drawings I have shown one embodiment of the invention. In this showing:

15 Figure 1 is a side elevation of the apparatus showing an airplane in flight about to pick up the loop connected to the article.

Figure 2 is a somewhat enlarged rear end elevation of the catapult mechanism and associated elements,

20 Figure 3 is an enlarged central vertical longitudinal sectional view through the catapult mechanism, parts being shown in elevation and parts being broken away,

Figure 4 is a transverse vertical sectional view on line 4—4 of Figure 3,

25 Figure 5 is a plan view of the catapult mechanism and associated elements,

Figure 6 is an enlarged central vertical sectional view through one of the loop supporting masts, parts being shown in elevation, and parts being broken away,

30 Figure 7 is a sectional view on line 7—7 of Figure 6, and,

Figure 8 is an enlarged central vertical sectional view through the fluid pressure motor, parts being shown in elevation.

35 Referring to Figure 1, the numeral 10 designates an airplane beneath which is suspended an arm 11 carrying a hook 12 at its lower end adapted to pick up the loop, to be referred to later, which is connected to the article or package to be picked up by the airplane.

The airplane is flown over a catapult mechanism indicated as a whole by the numeral 13, and it is this mechanism which projects the article to prevent the airplane from having to pick up a dead weight load. Referring to Figures 3 and 4, the catapult comprises longitudinally extending upper frame members 14 at opposite sides thereof, and each of these frame members is provided with a horizontal flange 15, for a purpose to be described. Lower angle iron frame members 16 also are provided and the sides of

40 the apparatus are closed by plates 17 as shown in Figure 4. The forward end of the apparatus, that is, the left hand end as viewed in Figure 3, is provided at least with a lower transverse frame member 18 and an end closure plate 19

members 14 and 16 and is secured to the transverse frame member 18.

At the rear end of the apparatus transverse angle iron frame members 20 and 21 extend across and are secured to the adjacent ends of the respective pairs of frame members 14 and 16. A relatively heavy end plate member 22 is secured to the transverse members 20 and 21. The forward end of the apparatus is supported by a caster wheel 23 having swivel connection as at 24 with a bracket 25 suitably secured to the end plate 22 and preferably to the transverse frame members 20 and 21. A draft connection 26 is preferably provided for the caster wheel 23 to permit the apparatus to be hauled behind a motor vehicle as a trailer. The opposite end of the apparatus is supported by wheels 27 which may be mounted on stub axles 28 secured in any suitable manner (not shown) to the lower frame members 16.

A catapult carriage indicated as a whole by the numeral 29 is provided for receiving and supporting an article 30 to be picked up by an airplane passing over the apparatus. The catapult carriage comprises a suitably shaped receptacle 31 for the article beneath which depends a frame structure 32. This frame structure may be of any suitable specific design and supports wheels 33 at opposite ends and at opposite sides of the carriage for rolling engagement with the flanges 15 whereby these elements act as trackways for the carriage. Referring to Figure 4 it will be noted that the wheels 33 are arranged relatively close to the frame members 14 whereby such members guide the carriage for linear movement. The frame structure 32 of the carriage is provided with a dependent boss 34 to the lower end of which is connected an elastic shock cord 35 of conventional type. It will become apparent that the present apparatus is not dependent upon any particular means for projecting the carriage but it has been found in practice that shock cords are particularly practicable for this purpose. While a single shock cord has been shown it will be apparent that any number may be employed depending upon the maximum load which it is desired to project on the carriage.

The shock cord 35 (Figure 3) is connected as at 36 to one end of a flexible belt 37 which passes around a pulley 38. The opposite end of the belt 37 is adapted to be wound about a drum 39 mounted on a shaft 40. This shaft is mounted in bearings 41 supported by a transverse member 42 connected at its ends to the frame members 16. A gear 43, mounted on the shaft 40, meshes with a pinion 44 carried by a shaft 45 also rotatably supported by the bearings 41. The shaft 45 projects from the side of the apparatus (Figure 4) and terminates in a polygonal end 46 engageable by an end of a crank arm and a ratchet 47 is engageable with a wheel 48 to prevent reverse rotation of the shaft 45. The means just described forms a windlass for the winding of the belt 37 to properly tension the shock cord 35, as will be apparent.

A spring pressed detent 49 (Figure 3) is carried by one end of the carriage 29. This detent is engageable by a hook 50 formed on one end of a bell crank lever 51 mounted on a shaft 52 supported by a bracket 53 which may be secured to the transverse frame member 20. A coil spring 54 normally urges the bell crank lever 51 to turn in a counter-clockwise direction to maintain the hook 50 in engagement with the detent 49. The lower end of the bell crank lever 51 is connected

to one end of a rod 55 which is pulled in a manner to be described to turn the bell crank lever and release the catapult carriage.

The releasing of the carriage 29 takes place upon the pulling of a loop 56 by the hook 12 (Figure 1) carried by the airplane. This loop, when in operative position, has downwardly and rearwardly converging portions 57 secured as at 58 to the article 30. The portions 57 extend upwardly and forwardly from the carriage 29 and are connected by a transverse portion 59 (Figure 2) supported in a manner to be described by the upper end portions of masts 60.

Each of the masts 60 is preferably formed of relatively light seamless steel tubing and each is supported at its lower end by a mushroom base 61 having a sleeve 62 receiving the lower end of one of the masts which is fixed thereto by a lock screw 63. The lower end of each tubular mast is sealed by a plug 64 (Figure 6). The upper end of each mast is provided with a valve body 65. Each valve body 65 has a passage 66 communicating with the interior of the associated mast, and with a passage 67 communicating with the atmosphere. A rotary valve 68 is mounted in each valve body 66 and is cut away as at 69 so as to disconnect the ports 66 and 67 or to connect these ports together upon the rocking of the valve.

Each valve 68 is provided with an upwardly extending forked arm 70 receiving a rubber or similar thimble 71 carried by the transverse portion 59 of the loop 56. The use of these thimbles, as will become apparent, is not important but their use is preferred for the reason that they provide sufficient frictional engagement with the forked arms 70 to insure the turning of the latter upon the picking up of the loop 59 by the hook 12. Moreover, the use of the thimbles eliminates direct wear on the loop 56, which is preferably formed of shock cord.

In order to properly support the masts 60 in vertical position and to properly space them each mast is slidable through a sleeve 72 which may rest directly upon the upper end of the adjacent sleeve 62. Each sleeve 72 may be fixed to its associated mast by a lock screw 73, and each sleeve 72 is carried by the outer end of an arm 74 (Figures 2, 4 and 6). Each of these arms is pivoted as at 75 to a bracket 76 connected to the side plates 17 and frame members 15 whereby the arms 74 may be swung inwardly to positions adjacent and parallel to the side plates 17 when the apparatus is to be moved from one point to another. Hook braces 77 (Figures 4 and 5) are adapted to hold the arms 74 in extended positions.

The present invention is provided with novel fluid pressure operated means for releasing the catapult latch comprising the elements 49 and 50. Referring to Figures 3 and 8, the numeral 78 designates a fluid pressure motor as a whole comprising casing members 79 and 80 having peripheral flanges 81 between which are clamped the peripheral portion of a flexible diaphragm 82 by means of clamping bolts 83. The diaphragm is preferably provided centrally thereof with stiffening plates 84 and a rod 85 extends axially through the diaphragm and through the plates 84 and is secured with respect to these elements by nuts 86. The diaphragm is provided with a leak port 87 preferably extending through the plates 84, for a purpose to be described. The rod 85 extends through a bearing 88 carried by the casing

79 and is pivotally connected as at 89 (Figure 3) to the adjacent end of the rod 55.

The casing 79 communicates through a conventional pressure regulator valve 90 with a hose or pipe 91 supported with respect to one of the side frame members 16 by clips 92. The hose 91 is connected to a fluid pressure tank 93, preferably through a cut off valve 94 (Figure 3). The pressure tank 93 may be supported at one side of the apparatus in the position shown in Figure 4. It will be apparent that the tank 93 may be charged with fluid under pressure from any source. Its capacity is a number of times that of the fluid pressure motor 78 and the tank may be charged to a pressure several times that which will be used in the motor 78. This ample fluid pressure will be available regardless of any minor leakage through the valves 68, for a substantial period of time.

The motor 78 may be fixed against axial movement by a relatively heavy stud 95 and may be further anchored in position by angular braces 96 (Figure 4) secured at their ends to the frame members 16. The stud 95 is connected to the casing 80 as shown in Figures 3 and 8.

The casing 80 is provided with a nipple 97 (Figure 8) connected to a T 98 from each branch of which a hose 99 leads to a nipple 100 tapped into one of the masts 60. Hoses 99 of a flexible nature are employed to permit the masts to be swung about the pivot 75 (Figure 4) as will be obvious.

Upon the releasing of the catapult carriage the tensioned shock cord 35 will move the carriage toward the left as viewed in Figure 3 with substantial force and at substantial speed. It is preferred that some cushioning means be employed for stopping the carriage adjacent its limit of travel. For this purpose a shock absorber 101 (Figure 3) is employed, and comprises telescoping tubes 102 and 103 in which a spring 104 is housed. The tube 103 may be secured to the end plate 19 while the inner end of the tube 102 is engaged by a portion of the carriage 29.

The operation of the apparatus is as follows:

The apparatus is intended for use where it is desired to pick up mail or other articles or packages at points where no landing field is available, or where it is desired to eliminate the time which would be required for a plane to land, pick up the articles or packages to be transported and then take off. The apparatus is hauled to a suitable spot with the arms 74 folded against the sides of the apparatus. These arms are then swung outwardly to their operative position, whereupon the masts 60 are ready to be placed in operative position. The article or package to be picked up is placed in the carrier 29 with the loop 56 connected thereto, whereupon the thimbles 71 (Figure 6) are inserted into the forked arms 70. The masts are then set up by sliding their lower ends through the sleeves 72 and into the sleeves 62, the lock screws 63 and 73 preferably being tightened after the masts have been set up. The valve 94 (Figure 3) may then be opened to admit fluid under pressure from the tank 93 into the motor casing 79, under the control of the pressure regulator valve 90. Air is preferably used as the pressure fluid, and it will be obvious that as the air flows into the casing 79, the leakage port 87 (Figure 8) permits air to flow into the casing 80 and through the T 98 and into the hoses 99 and masts 60. The leakage port 87, while of limited area, provides means for balancing pressures throughout the system, includ-

ing the balancing of pressures on opposite sides of the diaphragm 82. It will be apparent that when the apparatus is set up as described, the forked arms 70 (Figure 6) will be in their vertical positions to maintain the valves 68 closed. It is almost an impossibility to provide valves through which there will not be some minor leakage. In a system of the present character this leakage could become a serious matter, but the provision of the leakage port 87 prevents the pressure on opposite sides of the diaphragm 82 from becoming unbalanced except when the article is to be catapulted.

When pressures on opposite sides of the diaphragm 82 become equalized at the desired pressure of operation of the apparatus, the diaphragm 82 will be relatively freely movable except that it cannot be moved rapidly in either direction due to the limited area of the port 87. However, if the latch 50 has not been previously placed in engagement with the detent 49, the parts may be moved to the position necessary to latch the carriage 29 by pulling to the right on the rod 55, (Figure 3).

The operator will now rotate the shaft 45 by means of a crank applied to the polygonal end 46 thereof, whereupon the windlass will wind the adjacent end of the belt 37 on the drum 39. The belt 37 is employed for the reason that it is desirable to avoid passing the shock cord 35 around the pulley 38 or around the windlass drum. When the shock cords have been tensioned to their maximum point, the connection 36 will occupy approximately the position shown in Figure 3. The apparatus is now ready for operation.

The airplane which is to pick up the article 30 will fly over the apparatus in the direction indicated in Figure 1 with the hook 12 below the horizontal plane of the loop portion 59 and between the masts 60. Upon the engagement of the hook 12 with the loop portion 59, the latter element will be subjected to a quick pull which will be transmitted to both of the forked arms 70 to result in the turning of one or both of these arms. Inasmuch as it is impossible to perfectly equalize the pulling forces on the arms 70 the apparatus has been designed so that the turning of either of these arms will result in the releasing of the catapult.

Assuming that only one of the arms 70 will have been turned, the associated valve 68 will be turned equally to a position in which the valve cut-out 69 (Figure 6) affords full communication between the ports 66 and 67. Under such conditions pressure in the associated mast 60 will immediately drop and will result in a corresponding immediate drop in pressure in the motor casing 80 (Figure 8). The rate at which the pressure drops in the casing 80 will be many times greater than can be satisfied by the flow of air through the restricted port 87, and accordingly the air pressure in the casing 79 will immediately move the diaphragm 82 to the left as viewed in Figures 3 and 8, thus pulling on the lower end of the bell crank lever 51 to unlatch the catapult carriage. The tensioned shock cords 35 will then project the carriage 29 and the article thereon in the direction of travel of the airplane, and the apparatus is so designed that the tension of the shock cords will move the article, when it reaches the discharge end of the apparatus, at a speed approximating that of the plane. This speed will have been attained approximately at the point where the hook 12 will have straightened out the loop 56, and accord-

ingly the article will be picked up without any appreciable shock on the plane.

The hook 12 is preferably movable along the arm 11 by any suitable means forming no part of the present invention. By such means the loop may be pulled upwardly into the plane together with the package. Accordingly it will be apparent that the present apparatus permits the picking up of articles or packages of weights far above the relatively small weights which can be picked up without the use of a catapult. It is well known that only very limited dead weights can be picked up by a moving plane and the present apparatus greatly increases the weights of articles which can be picked up while at the same time eliminating the transmission to the plane of the shock occurring incident to the picking up of a dead weight load.

By the simple expedient of balancing pressures in the system, specifically by the provision of the bleed port 81, it is unnecessary to admit air pressure into both ends of the motor 78. The pressure balancing device referred to not only permits the connection of only one side of the motor to the source of pressure but also automatically compensates for any leakage which might occur through the valves 68.

In connection with the foregoing it will be obvious that without the pressure balancing means described, leakage might occur which could very easily progressively reduce pressure in one end of the fluid pressure motor so as to release the catapult prior to the arrival of the plane. It would then be necessary to re-set the apparatus while the plane circled above awaiting the completion of the re-setting operations. While the use of the pressure tank 93 is not essential its use is preferred. If the system were charged with air under pressure it would be necessary to provide the apparatus with a pressure gage since leakage through the valves 68 might reduce pressure in the system to such a point that there would be insufficient pressure in the casing 79 to release the catapult upon the picking up of the loop by the hook 12. The pressure tank with the pressure regulator valve 90 affords dependable means for maintaining proper operating pressures in the motor at all times. Thus the leakage port 81 will compensate for leakage of air from the system to maintain equalized pressure in the motor 78, while the pressure tank 93 and the pressure regulator valve 90 assure the maintenance in the motor of proper operating pressures.

It is to be understood that the form of the invention herewith shown and described is to be taken as a preferred example of the same and that various changes in the shape, size and arrangement of parts may be resorted to as do not depart from the spirit of the invention or the scope of the subjoined claims.

I claim:

1. In an airplane pick-up mechanism, a catapult having a carriage and a latch operative for holding the carriage against movement, a flexible element connected to an article supported by the carriage, means for supporting the flexible element in a position to be engaged by an airplane-carried element, and fluid pressure operated means for releasing said latch to release the carriage, said last named means having a portion carried by said supporting means and operable upon the picking up of said flexible element by the airplane-carried element.

2. In an airplane pick-up mechanism, a cata-

pult having a carriage and a latch operative for holding the carriage against movement, a flexible element connected to an article supported by the carriage, means for supporting the flexible element in a position to be engaged by an airplane-carried element, a fluid pressure operated device connected to said latch, and means for effecting the energization of said fluid pressure operated device to release said latch, said last named means having a portion carried by said supporting means and operable upon the picking up of said flexible element by the airplane-carried element.

3. In an airplane pick-up mechanism, a catapult having a carriage and a latch operative for holding the carriage against movement, a flexible element connected to an article supported by the carriage, means for supporting the flexible element in a position to be engaged by an airplane-carried element, a fluid pressure operated device connected to said latch and having a pressure movable element therein on opposite sides of which pressures are normally balanced, and means operative upon the picking up of said flexible element by the airplane-carried element for unbalancing pressures in said fluid pressure operated device to release said latch.

4. In an airplane pickup mechanism, a catapult having a carriage and a latch operative for holding the carriage against movement, a flexible element connected to an article supported by the carriage, means for supporting the flexible element in a position to be engaged by an airplane-carried element, a fluid pressure operated device connected to said latch, and valve means carried by said supporting means and operable upon the picking up of said flexible element by the airplane-carried element for effecting energization of said fluid pressure operated device to release said latch.

5. In an airplane pick-up mechanism, a catapult having a carriage and a latch operative for holding the carriage against movement, a flexible element connected to an article supported by the carriage, means for supporting the flexible element in a position to be engaged by an airplane-carried element, a fluid pressure operated device connected to said latch and having a pressure movable element therein on opposite sides of which pressures are normally balanced, and valve means operative upon the picking up of said flexible element by said airplane-carried element for unbalancing pressures in said fluid pressure operated device to release said latch.

6. In an airplane pick-up mechanism, a catapult having a carriage and a latch operative for holding the carriage against movement, a flexible element connected to an article supported by the carriage, means for supporting the flexible element in a position to be engaged by an airplane-carried element, a fluid pressure operated device connected to said latch, said fluid pressure operated device having a pressure movable member on opposite sides of which balanced non-atmospheric pressure is normally maintained, and means operative upon the picking up of said flexible element by said airplane-carried element for connecting one end of said fluid pressure operated device to the atmosphere to thereby establish differential pressures on opposite sides of said pressure movable element to release said latch.

7. In an airplane pick-up mechanism, a catapult having a carriage and a latch operative for

holding the carriage against movement, a flexible element connected to an article supported by the carriage, means for supporting the flexible element in a position to be engaged by an airplane-carried element, a fluid pressure operated device connected to said latch, said fluid pressure operated device having a pressure movable member on opposite sides of which balanced non-atmospheric pressure is normally maintained, and a valve device operable upon the picking up of said flexible element by the airplane-carried element for opening one end of said fluid pressure operated device to the atmosphere to thereby establish differential pressures on opposite sides of said pressure movable member to release said latch.

8. In an airplane pick-up mechanism, a catapult having a carriage, means tending to move said carriage in one direction, and a latch operative for holding said carriage against movement by said means, a flexible element connected to an article supported by the carriage, means for supporting the flexible element in a position to be engaged by an airplane-carried element, a fluid pressure operated device comprising a casing having a pressure movable member therein connected to said latch, the ends of said casing having restricted communication with each other to maintain balanced pressures on opposite sides of said pressure movable member, the ends of said casing being normally maintained at non-atmospheric pressure, and means operative upon the picking up of said flexible element by the airplane-carried element for opening one end of said casing to substantial communication with the atmosphere to rapidly establish unbalanced pressures on opposite sides of said pressure movable member to release said latch.

9. In an airplane pick-up mechanism, a catapult having a carriage, means tending to move said carriage in one direction, and a latch operative for holding said carriage against movement by said means, a flexible element connected to an article supported by the carriage, means for supporting the flexible element in a position to be engaged by an airplane-carried element, a fluid pressure operated device comprising a casing having a pressure movable member therein connected to said latch, said pressure movable element having a bleed port therethrough to maintain balanced pressures on opposite sides of said pressure movable member, the ends of said casing being normally maintained at non-atmospheric pressure, and means operative upon the picking up of said flexible element by the airplane-carried element for opening one end of said casing to substantial communication with the atmosphere to rapidly establish unbalanced pressures on opposite sides of said pressure movable member to release said latch.

10. In an airplane pick-up mechanism, a catapult comprising a carriage, a flexible element connected to an article supported by the carriage, means for supporting the flexible element in a position to be engaged by an airplane-carried element, a fluid pressure operated device having a pressure movable member therein on opposite sides of which balanced non-atmospheric pressure is maintained, means operatively connected to said supporting means and operative upon the picking up of said flexible element by the airplane carried element for unbalancing

pressures on opposite sides of said pressure movable member to effect movement of the latter, and means operatively connected to said movable member and operative by movement of said movable member for projecting said carriage.

11. In an airplane pick-up mechanism, a catapult comprising a carriage, a flexible element connected to an article supported by the carriage, means for supporting the flexible element in a position to be engaged by an airplane-carried element, a fluid pressure operated device having a pressure movable member therein, said device being normally subjected to non-atmospheric pressure and having a restricted leakage passage for maintaining such pressure normally balanced on opposite sides of said pressure movable member, means operatively connected to said supporting means and operative upon the picking up of said flexible element by the airplane carried element for unbalancing pressures on opposite sides of said pressure movable member to effect movement of the latter, and means operatively connected to said movable member and operative by movement of said movable member for projecting said carriage.

12. In an airplane pick-up mechanism, a catapult having a carriage, means tending to move said carriage in one direction, and a latch operative for holding said carriage against movement by said means, a flexible element connected to an article supported by said carriage, spaced masts for supporting the flexible element with a portion thereof in a position to be engaged by an airplane-carried element, a fluid pressure operated device energizable to release said latch, and a valve carried by the upper end of one of said masts and operative upon the picking up of said flexible element by the airplane-carried element for effecting energization of said fluid pressure-operated device.

13. In an airplane pick-up mechanism, a catapult having a carriage, means tending to move said carriage in one direction, and a latch for holding said carriage against movement by said means, a flexible element connected to an article supported by the carriage, a pair of masts one of which is tubular, a valve closing the upper end of said tubular mast and having an arm, a portion of said flexible element being supported by said arm and by the upper end of the other mast in a position to be engaged by an airplane-carried element, and a fluid pressure operated device having a pressure movable member connected to said latch and normally having balanced non-atmospheric pressure on opposite sides thereof, one end of said fluid pressure operated device communicating with said tubular mast whereby the picking up of said flexible element by the airplane-carried element will turn said arm to open said valve and thus unbalance pressures in said device to move said pressure movable member and release said latch.

14. In an airplane pick-up mechanism, a catapult having a carriage, means tending to move said carriage in one direction, and a latch for holding said carriage against movement by said means, a flexible element connected to an article supported by the carriage, a pair of masts one of which is tubular, a valve closing the upper end of said tubular mast and having an arm, a portion of said flexible element being supported by said arm and by the upper end of the other mast in a position to be engaged by an airplane-carried element, and a fluid pressure

operated device having a pressure movable member connected to said latch and normally having non-atmospheric pressure on opposite sides thereof, said device having a restricted leakage passage for normally balancing pressures on opposite sides of said pressure movable member, one end of said fluid pressure operated device communicating with said tubular mast whereby the picking up of said flexible element by the airplane-carried element will turn said arm and open said valve to connect said end of said device to the atmosphere, said valve being constructed to afford substantial communication between said end of said device and the atmosphere to unbalance pressures on opposite sides of said movable member to release said latch.

15. In an airplane pick-up mechanism, a catapult having a carriage, means tending to move said carriage in one direction, and a latch operative for holding the carriage against movement, a flexible element connected to an article supported by the carriage, means for supporting said flexible element in a position to be engaged by an airplane-carried element, a fluid pressure operated device comprising a casing and a pressure movable member therein operative for releasing said latch, means for supplying fluid under super-atmospheric pressure to one end of said casing, said device having a restricted leakage passage for normally maintaining both ends of said casing at balanced pressure, and means operative upon the picking up of said flexible element by the airplane-carried element for opening one end of said casing to the atmosphere to unbalance pressures in said device to thereby effect movement of said pressure movable member to release said latch.

16. In an airplane pick-up mechanism, a catapult having a carriage, means tending to move said carriage in one direction, and a latch operative for holding the carriage against movement, a flexible element connected to an article supported by the carriage, means for supporting said flexible element in a position to be engaged by an airplane-carried element, a fluid pressure operated device comprising a casing and a pressure movable member therein operative for releasing said latch, means for supplying fluid under super-atmospheric pressure to one end of said casing, said device having a restricted leakage passage for normally maintaining both ends of said casing at balanced pressure, and a valve connected to one end of said casing and constructed and arranged to be opened upon the picking up of said flexible element by the airplane carried element for opening said last named end of said casing to the atmosphere to unbalance pressures in said device to thereby effect movement of said movable member to release said latch.

17. In an airplane pick-up mechanism, a catapult having a carriage, means for moving said carriage in one direction, and a latch operative for holding the carriage against movement, a flexible element connected to an article supported by the carriage, means for supporting said flexible element in a position to be engaged by an airplane-carried element, a fluid pressure operated device comprising a casing and a pressure movable member therein operative for releasing said latch, said device having a restricted leakage passage for normally balancing pressures on opposite sides of said movable member, a tank for fluid under pressure, means comprising a

pressure regulator valve for admitting fluid under pressure from said tank to one end of said casing, and means for unbalancing pressures on opposite sides of said pressure movable member to release said latch upon the picking up of said flexible element by the airplane-carried element.

18. In an airplane pick-up mechanism, a catapult having a carriage, means for moving said carriage in one direction, and a latch operative for holding the carriage against movement, a flexible element connected to an article supported by the carriage, means for supporting said flexible element in a position to be engaged by an airplane-carried element, a fluid pressure operated device comprising a casing and a pressure movable member therein operative for releasing said latch, said device having a restricted leakage passage for normally balancing pressures on opposite sides of said movable member, a tank for fluid under pressure, means comprising a pressure regulator valve for admitting fluid under pressure from said tank to one end of said casing, and a valve connected to one end of said casing and constructed and arranged to be opened upon the picking up of said flexible element by the airplane-carried element to connect one end of said casing to the atmosphere to unbalance pressures on opposite sides of said pressure movable member to effect movement of the latter and release said latch.

19. In an airplane pick-up mechanism, a catapult comprising a carriage and power means for propelling said carriage, a flexible element connected to an article supported by said carriage, means for supporting said flexible element in a position to be engaged by an airplane-carried element, a fluid pressure operated device having a pressure movable member therein on opposite sides of which balanced pressure is normally maintained, means operatively connected to said supporting means and operative upon the picking up of said flexible element by the airplane-carried element for unbalancing pressures on opposite sides of said pressure movable member to effect movement of the latter, and means operatively connected to said pressure movable member and to said power means for rendering the latter effective for propelling the carriage upon movement of said pressure movable member.

20. In an airplane pick-up mechanism, a catapult comprising a carriage and power means for propelling said carriage, a flexible element connected to an article supported by said carriage, means for supporting said flexible element in a position to be engaged by an airplane-carried element, a fluid pressure operated device having a pressure movable member therein, said device being normally subjected to non-atmospheric pressure and having a restricted leakage passage for normally balancing pressures on opposite sides of said pressure movable member, means operatively connected to said supporting means and operative upon the picking up of said flexible element by the airplane-carried element for unbalancing pressures on opposite sides of said pressure movable member to effect movement of the latter, and means operatively connected to said pressure movable member and to said power means for rendering the latter effective for propelling the carriage upon movement of said pressure movable member.
